UNITED STATES PATENT OFFICE.

JOEL A. PRATT, OF MOUNT AYR, IOWA, ASSIGNOR OF ONE-HALF TO J. O. FRY, OF SAME PLACE.

SIGN.

SPECIFICATION forming part of Letters Patent No. 340,730, dated April 27, 1886.

Application filed August 14, 1885. Serial No. 174,431. (No model.)

To all whom it may concern:

Be it known that I, JOEL A. PRATT, a citizen of the United States, residing at Mount Ayr, in the county of Ringgold and State of Iowa, have invented a new and useful Improvement in Signs, of which the following is a specification, reference being had to the accompanying drawings.

My invention relates to improvements in advertising-signs; and the novelty consists in the construction, combination, arrangement, and adaptation of the several parts for service, substantially as hereinafter fully set forth, and particularly pointed out in the claims.

15 It is the object of my invention to provide an advertising-sign which shall be capable of rotation by the wind; which can be regulated to revolve a certain number of times, so that when the strength of the wind increases above. 20 the estimated strength to which the device is proportioned and arranged it will only revolve its certain number of times; which shall give forth when the sign proper is in motion a number of musical sounds in consonance 25 with each other, and so arranged and sounded that they produce the tune of some popular air or ballad to attract the attention of passers-by to the sign, and which shall combine strength, simplicity, and durability of construction with cheapness of manufacture and 30 efficiency in operation.

I have shown an embodiment of my invention in the accompanying drawings, in which Figure 1 is an elevation of an advertising-sign 35 embodying my invention. Fig. 2 is a vertical central section thereof on the line *x x* of Fig. 5. Fig. 3 is a detailed view of one of the sectional collecting-hoods; and Fig. 4 is a detail view of one of the bells and its sounding mechanism, which comprise the means for producing the musical sounds which compose the tune, &c. Fig. 5 is a horizontal section.

Like letters of reference indicate like or corresponding parts in all the figures of the 45 drawings.

Referring to the drawings, A designates the central supporting-standard, secured in a base, A', rigidly secured to a floor or other place.

B designates the sign-frame, preferably 50 square in shape, and adapted to rotate horizontally around the standard or pole A. The

frame may be hexagonal, octagonal, circular, or other shape, and comprises a series of vertical bars, B', arranged a suitable distance from each other and connected at their ends by horizontal cross-bars B², which meet together at the standard, and are secured to a plate or plates, or together, in any preferable manner. The upright bars may be secured directly to a flat plate or bar, which is journaled upon the standard A, so as to be capable of rotating freely around the same to display the sign in different directions and operate the striking mechanism to the bells or chimes.

65 The upright bars of the revolving frame have secured to their exterior faces a covering of cloth, muslin, cotton, or other fabric or material, as at C, by means of tacks, nails, or otherwise, and on which the signs, figures, &c., are painted or affixed in any suitable or preferable manner.

D designates a ring or band arranged around the upright or standard A at some distance therefrom, and within the frame B a short distance from the vertical bars B' thereof. The rings or bands are arranged in series, one above the other, and the number of rings corresponds to the number of bells E on which the notes are sounded which produce the tune or air.

75 The devices for producing the sounds are operated on the principle of the chime-bells or the music-box, and are operated automatically by the sign-frame revolving around the frame-supporting standard, the time or rapidity of the tune or air being governed by the 80 number of revolutions of the sign-frame. Each ring or band is held in position by a series of wings or bars, F, secured upon each of the uprights B', and connected thereto and to the ring in any preferable manner. The ring or band is provided with a series of inwardly-projecting pins, e, arranged at suitable intervals apart, as will be more fully 85 described, and adapted to operate the bell-striking lever, G, supported in a frame, H. The frame H comprises vertical bars H', connected at their upper and lower ends by cross-bars H², rigidly secured to the post or standard A, said frame having a series of vertical 90 slots, h h, formed in the upright bars thereof,

through which the bell-striking levers G pass, the outer end of said levers being pivoted in the outer vertical bar of the frame H, as at g, and provided with a weight, G', to keep the outer end thereof depressed below the inner end, so that when the band or ring is rotated with the sign-frame the projections or pins thereof are successively brought in contact with the weighted end of the lever and depress the same, thus causing it to move on its pivot, and elevate the inner end thereof, and after the pin ceases to act on the outer end of the bell-striking lever the inner end thereof falls and strikes its bell and gives forth the proper note or sound. The inner end of the lever works in an elongated slot in the inner upright bar of the frame H, and is kept normally elevated above the pivot and outer end thereof by the weight G' on said outer end. Each standard of the frame H may be composed of two vertical strips arranged a short distance from each other and connected by a series of stops secured on one face thereof.

25 E E designate bells secured in any preferable manner upon the standard A, and arranged in series thereon on the face thereof, adjacent the levers G, and below the plane of the pivot thereof. The number of bells corresponds to the number of bell operating or striking levers or mechanisms, and to the number of notes which comprise the air or tune, each bell having a different tone and operated or struck by the lever G.

35 The pins or projections in the ring or band are arranged at different or varying distances apart around the same to operate the bell-levers the desired number of times to produce the required notes in succession and consonance. The nearer together the pins are arranged the greater the number of blows given to the bell and the shorter the notes, while the farther apart said pins are arranged from each other in the band the fewer the number of blows given to the bell and the longer the notes will sound. Each bell having a tone and the pins in each of the bands being arranged at varying distances apart to suit the requirements of the case, an air or tune of any popular song can be played upon the bells, thus greatly increasing the effectiveness of the device by drawing the attention of the passers-by to the sign.

45 The sign-frame is adapted to be revolved by the force or power of the wind and is placed out of doors.

55 Each of the vertical standards of the sign-frame is provided at its upper edge with a cross-bar, I, suitably secured thereto, and to said cross-bar is secured a collecting-hood, J, by means of nails, screws, or other preferable means, passed through the lower surface thereof into the cross-bar. The collecting-hoods are preferably cone-shaped, as shown, and are arranged in an approximately horizontal position and at different angles to each other, and adapted to catch the wind, the force or

power of which serves to propel the same and the sign-frame to which it is secured around and present the succeeding hood J to the action of the wind, each hood being successively presented to the action of the wind and rotating the sign-frame in a horizontal plane.

60 The hood is made hollow and of light sheet metal, and it is supported on the revolving sign-frame in a slightly-inclined position. The apex of the hood may be arranged to project below the upper edge of the sign-frame, so that it will lie in a position to utilize the force of the wind, that acts to a greater extent on the upper section of the hood.

65 The hood is made in two longitudinal sections, J', which fit together and are of equal size, the forward or larger ends thereof having two perforated ears or lugs, j, which register with corresponding ears on the adjacent section, and are pivoted together, as at l, to permit the inner reduced ends thereof to open when the strength of the wind has increased above the estimated strength to which the hood is proportioned, thus permitting the wind to pass through the hood, and obviating the danger of overturning or upsetting the device.

70 The operation of my invention is obvious from the foregoing description. The sign-frame is rotated in a horizontal plane by the wind striking against the collecting-hoods, and carries with it the bands or rings that carry the pins which operate the bell-striking levers and sound the notes on the several bells in consonance and proper order and time to produce the tune to which the device has been set and arranged. The standard A and the frame H are rigid and immovable when the device is in use, although they can be readily transported from place to place, while the sign-frame is revoluble to cause the pins to act upon the bell-striking levers.

75 In lieu of pins on the ring or track, a series of cam projections may be provided, and a spring may be substituted for the weight on the lever G, and other modifications in form and proportion of parts and details of construction may be made without departing from the principle or sacrificing the advantages of my invention, the essential parts of which will be readily understood from the foregoing description, taken in connection with the drawings.

80 In lieu of the devices for revolving the sign-frame by wind-power, I also propose to propel or revolve the same by weight or spring power connected thereto in any suitable or preferable manner.

85 Having thus fully described my invention, what I claim as new, and desire to secure by Letters Patent, is—

1. The combination of a rigid supporting-standard, a horizontal rotatable sign-frame journaled on the standard, and a series of collecting-hoods rigidly secured in a horizontal or approximately horizontal position on the sign-frame at the upper edges thereof and disposed at different angles to each other, each

hood being made cone-shaped and comprising two longitudinal sections that are pivoted together at their enlarged ends and adapted to be opened at their reduced ends when the force of the wind increases above the strength of the wind to which the sections of the hood are proportioned, substantially as described.

2. The combination of a rigid standard, a rotating sign-frame mounted thereon and carrying bands or rings provided with lever-operating means, a series of bells, and movable bell-hammers arranged to be actuated by the said means on the rings or bands to strike the bells when the sign-frame is rotated, substantially as described.

3. The combination of a rigid standard, a horizontally-rotatable sign-frame supported thereon, and having rings or bands provided with lever-operating means, a series of bells of different tone or quality, and a series of pivoted bell-hammers adapted to be operated by the devices on the rings or bands to strike the bells, substantially as described.

4. The combination of a rigid supporting standard, a rotatable sign-frame journaled thereon, and provided with rings having operating devices, a series of bells of different tones, a frame, and a series of bell-hammers supported in the frame and adapted to be operated by the operating devices on the bands of the sign-frame to strike the bells, substantially as described.

5. The combination of a rigid standard, A, a horizontally-rotatable sign-frame supported thereon, a series of rings or bands secured to the said frame and provided with spaced pins, a series of bells of variable tone or quality, a

rigid frame supported on the standard, and a series of bell-hammers pivoted in the rigid frame and having their ends free to be acted on by the pins and to strike the bells, substantially as described.

6. In a sign, the combination of a vertical rigid standard, A, a horizontally-rotatable sign-frame supported thereon, a series of rings or bands, D, secured on the sign-frame and provided with spaced pins e, a series of bells mounted on the standard, a rigid frame, H, secured to the standard and having an inner and outer upright, and a series of bell-hammers pivoted in the outer upright of the frame and having their opposite ends guided in the inner upright of said frame, substantially as described.

7. In an advertising-sign, the combination of a supporting-standard, a horizontally-revolving sign-frame mounted on said standard, a series of rings secured to the sign-frame and having a series of pins, a series of bells secured on the standard, a lever-supporting frame secured to the standard and slotted, as described, a series of bell-striking levers having a weighted end and pivoted in the supporting-frame, and a series of sectional pivoted collecting-hoods mounted on the sign-frame, substantially as described.

In testimony that I claim the foregoing as my own I have hereto affixed my signature in presence of two witnesses.

JOEL A. PRATT.
